O. S. GARRETSON, OF BUFFALO, NEW YORK,

Letters Patent No. 65,662, dated June 11, 1867.

IMPROVED MOP-HEAD.

The Schedule referred to in these Letters Patent and making part of the same.

TO ALL WHOM IT MAY CONCERN:

Be it known that I, O. S. GARRETSON, of the city of Buffalo, in the county of Erie, and State of New York, have invented a new and useful improvement in Mop-Heads; and I do hereby declare that the following is a full and exact description thereof, reference being had to the accompanying drawings, making part of this specification, in which—

Figure 1 is an elevation; and

Figure 2 a fragmentary section of the adjusting nut E and collar D of the movable jaw-frame C.

Like letters indicate corresponding parts in both drawings.

My improved mop-head consists essentially of three parts, viz, a screw-shank and cross-head A B, preferably cast as one piece of metal; a jaw-frame C, provided with a collar or socket, D, for the screw-shank A; and a nut, E, by means of which the jaw-frame C is made to move to and from the cross-head or stationary jaw B to compress or release the mop-cloth, the sides of the jaw-frame sliding in recesses f f in the ends of B to guide their movement. In connecting the jaw-frame with the adjusting nut, I prefer to employ the device shown, consisting of an annular flange, h, on the nut, in combination with lips or lugs i i on the sides of the collar, which embrace the flange h, but allow free rotary motion of the nut, which, when turned, causes the collar and jaw-frame to advance or recede with it along the screw-shank, and thereby bring the jaw-frame C nearer to or remove it from the fixed jaw or cross-head B; but this I do not claim, it having been patented to Charles B. Clark and O. S. Garretson, May 22, 1866. But my invention is not limited to the combination of this device, as it is obvious that by threading the socket D to form a nut for the screw-shank A, and pivoting the latter to the cross-head, the nut E may be dispensed with, and the two jaws made to perform their functions of approaching and receding by simply turning the handle G if connected rigidly with the shank, so as to revolve the latter. A like movement of the jaws would also be obtained by making the screw of the shank A as a sleeve, turning on the fixed shank of the cross-head, in connection with the threading of the collar D; and in either of these modifications, which I regard as equivalents in respect to my improvement, the utmost simplicity is maintained, and only the three pieces of metal are required to form the mop-head.

My invention consists in the formation of the jaw-frame or moving jaw C of a single piece of metal, in combination with the fixed jaw B and its guiding recesses f f; the moving jaw C being provided with a collar, D, which works upon the shank A.

The movable jaw of mop-heads is usually formed of wire, bent to enclose the fixed jaw, and the two ends passed through lugs on the collar or nut which surrounds the shank, and secured by rivet heading. This involves considerable labor, and liability of breaking so small a casting as the collar, increasing the cost too greatly for an article which must be sold at a low price; and it greatly diminishes the durability of the head, as the riveted ends become loose and break off in a short time from the rough usage incident to the implement. But the forming of this jaw and collar of one piece of metal, which may be of wrought or malleable cast iron, obviates both objections, as it dispenses with the cost of riveting, also with joints that are subject to become loose, and thereby increases the durability of the article indefinitely. The necessity of forming the jaw-frame elongated at one extremity before putting together exists in the fact that the screw-shank must necessarily be of considerable length in order to secure sufficient range of motion of the jaws one upon the other to admit of the insertion of the mop-cloths between, and then removed.

What I claim as my invention, and desire to secure by Letters Patent, is—

The jaw-frame and socket C D, composed of a single piece of malleable metal, in combination with the cross-head B, and screw-shank A, or its equivalent, when said jaw and socket have a reciprocating movement in consequence of the revolving of the socket; or of a nut connected therewith, or of the screw within the same, substantially as herein described.

In witness whereof I have signed my name in the presence of two subscribing witnesses.

O. S. GARRETSON.
